APPAREL LABEL

Leo Grabenstein, Long Beach, N. Y.

Application January 16, 1940, Serial No. 314,022

3 Claims. (Cl. 40—2)

This invention relates to labels of the kind that are applied to shirts, pajamas and other articles of apparel.

It is customary for the manufacturer to sew his own labels on the articles, usually in an early stage of their manufacture. These labels may be termed manufacturers' labels or stock labels; the term "manufacturer's label" will be used in this specification. The invention is an improved apparel label suitable for use as a manufacturer's label.

A manufacturer's label ordinarily carries the particular manufacturer's name, trade-mark, or trade-name, and in addition it may bear a size mark or other matter descriptive or indicative of the article, its material, its cut, color-fastness, sewing, etc.

To promote their good-will many retailers and some jobbers require the manufacturer to apply their own labels, which for convenience may be termed "customers' labels," and the general desire, when this is done, is that the manufacturer's label should not show. In some instances the manufacturers' labels are removed, but this takes time and involves expense; furthermore some garments are damaged in the operation and become seconds or thirds.

Therefore, it is common practice to put the customer's label over the manufacturer's label. If the customer's label is not large enough to cover the manufacturer's label, the resulting appearance is such that the advantage accruing to the retailer or jobber from his own label is partly lost, and the public may conclude that the goods are seconds or "close-outs." Many retailers choose to have comparatively small labels. It is one of the advantages of this invention that, though the customer's label need not completely cover the manufacturer's label, benefit of customers' labels is not sacrificed and the public is not led to under-rate the goods.

According to this invention the main part of the manufacturer's label and all or practically all of the stitching that secures this label to the garment may be concealed by the customer's label, but a part of the manufacturer's label displaying descriptive matter (size, material, cut, or color-fastness, sewing, etc.) may be left exposed, not only without detriment but to advantage. Thus, it is unimportant whether the customer's label be larger in both dimensions than the manufacturer's label, and the extending part of the manufacturer's label takes the place of separate size markers and the like, with consequent saving.

In the accompanying drawing illustrating certain embodiments of the invention:

Fig. 1 is a face view, slightly in perspective, of a manufacturer's label attached to a portion of a garment;

Fig. 2 is a section on the line 2—2 of Fig. 1;

Fig. 3 is a view like Fig. 1, but showing a customer's label secured over the manufacturer's label;

Fig. 4 is a view like Fig. 1, showing a modification;

Fig. 5 is a face view of a label of the invention of different form than that shown in Fig. 1; and

Fig. 6 is a view like Fig. 5 with a customer's label superimposed on the manufacturer's label.

In Figs. 1—4 a label element of the invention is designated by reference numeral 2, and a portion of the garment is designated by reference numeral 3. The label element may be made in ribbon or tape form of textile fabric and be supplied in rolls in the customary manner. Assuming the label elements to be thus made, the selvage edges are 4, 4 and the raw edges are 5, 5.

The main indicia section 6 of the manufacturer's label 2 is shown attached to the garment 23 by stitching on the lines 7^a, 7^b, 7^c and 7^d. A narrow portion 8 carrying one of the raw edges is turned under and caught by the stitching 7^a in customary manner.

The part 9 of the label comprises a second indicia section and is for the display of descriptive matter, represented in the drawing by the size mark 11. For convenience and without limitation on the matter displayed, the section 9 may be termed a marker section. Adjoining and continuous with the section 9 there is an extension comprising a blank section 12, which carries the other raw edge and which is turned under the part 9. It will be observed that the parts 9 and 12 are broad and that the part 12 is caught by the stitching 7^b, 7^c, 7^d, which can be concealed by a later-applied customer's label which does not cover the section 9. In other words, the stitching does not extend, or materially extend, into the marker section, the marker section being substantially outside the stitched area. The parts 9 and 12 form a loop 14, on the face of which is the size mark or other incidental descriptive matter.

Fig. 3 shows a customer's label 15, which has been stitched or otherwise secured over the label 2, covering all the main part of the latter label, and covering also the stitching 7^a, 7^b, 7^c, 7^d, but leaving exposed the free loop 14 and its exhibited matter.

After the customer's label is attached to the

garment, the extending loop 14 does not suggest the presence of an underlying label, but rather gives the finished effect of a marker loop or the like that was inserted at the time the store label was sewed on.

Fig. 4 illustrates an additional advantage of the label of the invention and an economical manner of applying it to the garment. The line of stitching 7^c of Fig. 1 that is nearest the loop 10 is omitted in Fig. 4. This is permissible since the lower portions of the side lines of stitching 7^b and 7^d go through the under part of the loop, holding it firmly to the garment and preventing the loop from opening up. In this way the manufacturer can save a considerable part of sewing time and expense.

The label 2^a of Figs. 5 and 6 differs in shape from that of Figs. 1-4 but the principle is the same, and similar parts and features of the labels are designated by the same reference numerals. The label 2^a is of the long, narrow type which extends horizontally when secured to the garment, and which is sometimes termed a hanger or hanger label. If it is a true hanger it is 25 stitched to the garment at the ends only of the main part 6. In this label the loop 14 extends at one side, instead of at the bottom as in Figs. 1-4.

I claim:

1. In combination with an article of apparel, 30 a label element with two contiguous indicia sections and a blank section beyond the second indicia section and longer than said second indicia section, and stitching extending through the label element to secure said element to the apparel, said stitching including stitches that extend across the label element between the indicia sections, the blank section of the label element being turned back under the second indicia section to lie between the second indicia section 35 and said article of apparel, and the blank sec-

tion being held to the article of apparel by said stitches that extend across the label element between the indicia sections.

2. In combination with an article of apparel, 5 a label element including a main section having indicia on its outer surface and stitched to said article along at least two parallel edges, a marker section facing in the same direction as the main section and integral with the main section along one of said parallel edges, and an extension along 10 the edge of the marker section remote from its connection with the main section, said extension being folded under the marker section between the marker section and the article of apparel and forming with the marker section a loop of sufficient size to serve as a hanger, the folded-under end of the extension being secured by the stitching that secures one of the parallel edges of the main section to the article of apparel.

3. In combination with an article of apparel, 20 a label element including a main section having indicia on its outer surface and stitched to said article along at least two parallel edges, a marker section facing in the same direction as the main section and integral with the main section along 25 one of said parallel edges, an extension along the edge of the marker section remote from its connection with the main section, said extension being folded under the marker section between the marker section and the article of apparel and 30 forming with the marker section a loop, the folded-under end of the extension being secured by the stitching that secures one of the parallel edges of the main section to the article of apparel, and a second label element stitched to the 35 article of apparel and overlying the main section and the stitching of the first label element, leaving only the loop of the first label element exposed.
